Mr. Justin
Horace Williams

Inventor;

George H. Kidney

UNITED STATES PATENT OFFICE.

GEORGE H. KIDNEY, OF CLEVELAND, OHIO.

IMPROVED CLOTHES-WRINGER.

Specification forming part of Letters Patent No. 35,910, dated July 22, 1862.

To all whom it may concern:

Be it known that I, GEORGE H. KIDNEY, of Cleveland, in the county of Cuyahoga and State of Ohio, have invented a new and useful Improvement in Machines for Wringing or Pressing the Water from Clothes; and I do hereby declare that the following is a full and exact description thereof, reference being had to the accompanying drawings, and to the letters of reference marked thereon, making part of this specification.

The nature of my invention consists in slotted angular curved levers and angle-springs acting upon rubber rollers, and self-adjusting levers acting upon the tub.

Figure 1 is a front view showing the rollers, levers, and spring-boxes. Fig. 2 is an inside view of one end as attached to a tub, the tub shown in section. Fig. 3 is an enlarged top view. The red lines represent parts of the machine which are not visible. The letters of reference show the same parts of the machine as those in Figs. 1 and 2.

A A² in Fig. 1 are rubber rollers as used in the various kinds of clothes-wringers. B B are the ends, which support the rollers, levers, and springs. C C² are two rods which hold the ends B B in their place. D D are boxes which contain the springs. E E are slotted angular curved levers which press the top roller, A, down upon the bottom roller, A². F F are self-adjusting levers placed upon the rod C², which hold the machine fast to the tub when in use.

A A² in Fig. 2 are end views of the rollers. E is a side view showing the slot and curve of the angular curved lever. D is a box containing the spring shown by the red lines, which acts upon the curved end of the lever. The box and spring are set upon an angle having a tangential relation to that part of the periphery of a circle through which the eye in the curved end of the lever passes, in which the wire or rod plays which connects the bottom of the spring to the lever, thereby allowing an easy action of the spring and lever.

Rubber springs may be used. The slot a in the fulcrum end of the lever allows the upper roller, A, to move in the slot b without binding or rubbing on either side. H H² are jaws between which the tub is fastened. F is a self-adjusting lever hung upon the rod C² near the bottom of the jaw H. The lower or short arm of the lever F is curved toward the jaw H². The upper or long arm of the lever F is straight. The red lines show the position of the lever just before attaching the machine to the tub. As the machine is placed upon the tub and pressed down, the upper edge of the tub comes in contact with the upper or long arm of the lever, pressing it back, thereby causing the curved or lower arm of the lever to be pressed tightly against the tub, causing the machine to be held firmly upon the tub.

A in Fig. 3 is the top roller, upon which the slotted angular curved lever acts. B B are the ends, angled to the right and to the left from the front of the rollers. C C² are rods which hold the ends in place. D D are boxes or pockets which contain the springs, as described above. E E are slotted angular curved levers angled to the right and to the left, corresponding with the angle of the ends B B. The ends and levers being angled allow the clothes to pass freely between them after being wrung. F F are self-adjusting levers working on the rod C², as described before.

After thus describing my machine, and being acquainted with many of the various wringers, I do not claim in the abstract the rollers, levers, springs, or jaws; but

What I do claim, and desire to secure by Letters Patent, is—

The combination of the slotted angular curved levers E E, rollers A A, springs in boxes D D, the jaws H H², and self-adjusting levers F F, all arranged as and for the purpose specified.

GEORGE H. KIDNEY.
